WINDOW GUARD

Samuel Levin, Hartford, Conn.

Application March 12, 1952, Serial No. 276,128

11 Claims. (Cl. 20—71)

This invention relates to a device of the class commonly known as window guards. Such a device includes a main frame adapted to be mounted at a window, a closure hinged to the main frame and movable to or from a closed position, and means carried by the closure and relatively movable into and out of engagement with the main frame for retaining the closure in closed position or for releasing it. While usually referred to as a window guard, a device of this class is adapted for use at any wall opening.

A window guard of the class described ordinarily includes a handle at one side, usually the inner side, for relatively moving the retaining means for retaining the closure in closed position or for releasing it. A lock is usually associated with the retaining means or with the handle to lock the retaining means in retaining engagement with the main frame. It is desirable to provide a second handle accessible at the opposite side, usually the outer side, for moving the retaining means to releasing position in the event of fire or other emergency. One object of the invention is to provide an improved construction including a second handle, such as last above described, located at the said opposite side and adapted for moving the retaining means to releasing position.

When a second handle is provided at the said opposite side as above stated and when a lock is provided, it is necessary for the lock to be so constructed or located that it is accessible at each side for manual unlocking. Another object of the invention is to provide a window guard having two oppositely located handles as described and having a lock accessible at each side.

Other objects of the invention are to provide various details of construction and arrangement whereby the foregoing more general objects are advantageously obtained.

In the drawing I have shown in detail two embodiments of the invention, but it will be understood that various changes may be made from the constructions shown, and that the drawing is not to be construed as defining or limiting the scope of the invention, the claims forming a part of this specification being relied upon for that purpose.

Of the drawing:

Fig. 1 is a front view of a window guard embodying the invention.

Fig. 2 is an enlarged front view of a portion of the window guard as shown in Fig. 1.

Fig. 3 is a fragmentary horizontal sectional view taken along the line 3—3 of Fig. 2.

Fig. 4 is a fragmentary horizontal sectional view taken along the line 4—4 of Fig. 2.

Fig. 5 is a fragmentary vertical sectional view taken along the line 5—5 of Fig. 2.

Fig. 6 is a fragmentary front view similar to Fig. 1 but showing an alternative embodiment of the invention.

Fig. 7 is an enlarged fragmentary vertical sectional view taken along the line 7—7 of Fig. 6.

Referring to the drawing and more particularly to Figs. 1 to 5 thereof, 10 is a rectangular main metallic frame

2

adapted to be secured in place at a window or at another wall opening. As shown, the frame 10 comprises angle bars suitably connected at the corners by welding or otherwise. Ordinarily the main frame 10 is located within the window opening in the wall and is located at the inner side of the window sashes.

A closure is provided for the area within the main frame 10, this closure including a second rectangular metallic frame 12 of such size as to fit within the main frame 10. As shown, the frame 12 comprises channel bars suitably connected at the corners by welding or otherwise. The closure frame 12 is hinged to the main frame 10 at one edge thereof, and as shown it is hinged at the right edge by means of hinges 14, 14. The closure also includes suitable closure material, such as wire mesh 18 secured at its edges by welding or otherwise to the closure frame 12. An intermediate reinforcing member is preferably secured to the edge members of the closure frame 12 and this may comprise two opposed channel bars 20, 20 at opposite sides of the mesh 18. The closure has opposite sides and it is so formed or constructed as to prevent manual access therethrough from either side to the other. As stated, the closure material may include wire mesh such as 18, but the openings through the mesh are not of sufficient size to permit manual access therethrough.

Carried by the closure at or near the edge thereof opposite the hinges 14, 14 is a retaining means which is relatively movable into and out of engagement with the main frame 10 for retaining the closure in closed position or for releasing it. Two manually operable handles are carried by the closure and are respectively located at and accessible at the opposite sides thereof. These handles are connected with the retaining means for moving it into and out of retaining engagement with the frame. The retaining means and the operating handles therefor may be widely varied as to details of construction and arrangement. One suitable construction and arrangement is shown in Figs. 1 to 5 and this will now be described in detail.

Secured to the left edge member of the closure frame 12 is a vertical plate 22. The wire mesh 18 is cut away to provide space for the plate 22 and the edges of the mesh are secured to the said plate as shown in Figs. 3 and 4. A manually operable handle 24 is horizontally pivoted to the plate 22 at 26, the said handle being near the top of the plate and at the front or inner side thereof. The handle 24 is provided at its left end with an extension 28 which is normally positioned within a vertical slot formed in a plate 30 secured to the left edge member of the main frame 10. The extension 28 constitutes one portion of the before-mentioned retaining means and when entered in the slot in the plate 30 the said extension serves to assist in retaining the closure in closed position. When the handle 24 is moved to the position shown by dotted lines in Fig. 2, the extension 28 is swung upwardly out of the slot so as to at least partly release the closure.

Pivotedly connected with the handle 24 at opposite sides of the pivot 26 are rods 32 and 34 which extend respectively upwardly and downwardly. The upper end of the rod 32 extends through a small plate 36 carried by the upper member of the closure frame 12 and into an aperture in a similar small plate 37 on the upper member of the main frame 10. Similarly the lower end of the rod 34 extends through a small plate 38 carried by the lower member of the closure frame 12 and into an aperture in a similar small plate 39 on the lower member of the main frame 10. The rods 32 and 34 cooperate with the handle extension 28 to constitute the said retaining means for the closure. When the parts are in the relative positions shown in Fig. 1, the handle extension 28, the upper end of the rod 32, and the lower end of

the rod 34 all cooperate to retain the closure in closed position. When the handle is moved to the position shown by dotted lines in Fig. 2, the handle extension 28 is moved out of the slot in the plate 30 as previously stated and the rods 32 and 34 are moved respectively downwardly and upwardly so as to withdraw their end portions from engagement with the small plates 37 and 39 on the main frame. Thus the closure is released so that it can be swung on the hinges 14, 14.

A manually operable handle 40 is horizontally pivoted to the plate 22 at 42, the said handle being substantially spaced downwardly from the handle 24 and being at the opposite or rear side of the said plate 22. A link 44 is provided having its lower end pivotally connected at 45 with the handle 40, the last said pivotal connection being at the left of the pivotal connection 42. The upper end portion of the link 44 is bent forwardly and extends through an arcuate slot 48 in the plate 22. The forwardly extending portion of the link 44 is pivotally connected with the handle 24, a common pivotal connection being provided for the upper end of the link 44 and the upper end of the rod 34.

As has been pointed out, the handles 24 and 40 are at opposite sides of the closure. The handle 24 is accessible only at the front or inner side and the handle 40 is accessible only at the rear or outer side. The handle 24 is adapted to serve for relatively moving the retaining means as described and the said handle 40 is also adapted for relatively moving the retaining means in the same manner.

The handle 40 is preferably at a considerably lower level than the handle 24. The handle 24 is positioned for convenient operation from the inside of a building and this is the handle which is normally used. In the event of a fire or other emergency the handle 40 may be used for operating the retaining means and the position of this handle at a lower level makes it possible for the said handle to be more readily reached from a ladder at the outside of the building.

A manually operable lock is provided which has a single operating means and which normally serves to lock the retaining means in retaining engagement with the main frame and this lock is so constructed and arranged that the operating means thereof is accessible at each side of the closure for manual unlocking so as to release the retaining means for movement by either handle out of its said retaining engagement with the main frame. This lock and the parts associated therewith may be variously constructed and arranged. One suitable construction and arrangement is shown in Figs. 1, 2, and 5 and this will be described in detail.

Carried by the closure and preferably by the plate 22 is a relatively movable member, this member being connected for movement with the retaining means and with the handles. Preferably the said member is an integral downward extension 50 on the handle 40, this being located immediately adjacent the plate 22 and at the rear or outer side thereof. The said member or extension is movable in parallelism with the face of the plate. The plate 22 and the extension or member 50 are provided respectively with apertures 52 and 54 which are in register with each other when the retaining means is in its frame engaging position as shown. The plate 22 is provided with a small opening 56 immediately below the apertures 52 and 54 and of such size as to be adapted to receive the body 58 of a padlock. The shackle 60 of the padlock extends through the apertures 52 and 54 and serves to prevent relative movement of the member 50, thus serving to prevent movement of the retaining means out of its main frame engaging position. The padlock body 58 may have the usual keyway in its lower end for receiving a key, and upon manipulation of the key one leg of the shackle is released in the usual manner. The key and the lock parts associated with the keyway constitute the said single operating means for the lock.

The opening 56 is of sufficient depth to permit the padlock body 58 to move downwardly relatively to the shackle 60 upon unlocking. For a reason hereinafter stated, the apertures 52 and 54 are slots substantially perpendicular to the adjacent edge of the opening 56. The said slots have lengths greater than the major transverse dimension of the padlock shackle 60.

It will be observed that the operating means of the padlock is accessible at each side of the closure. For unlocking, the padlock can be swung toward the front or toward the rear as indicated respectively at 58^a and 58^b in Fig. 5.

If it be assumed that the padlock is in position 58^a at the front and that the shackle 60 is released at the front of the body 58 upon unlocking, the said shackle after release can be pushed rearwardly through the slots 52 and 54 and then moved downwardly and withdrawn forwardly through the opening 56, as indicated at 58^c. If it be assumed that the padlock is in position 58^b at the rear and that the shackle 60 is released at the front of the body 58 upon unlocking, the said shackle after release can be pushed forwardly through the slots 52 and 54 and then moved upwardly and withdrawn rearwardly through the said slots as indicated at 58^d in Fig. 5. The described lengths of the slots 52 and 54 make it possible for the padlock to be moved to position 58^d.

Figs. 6 and 7 show an alternative embodiment of the invention, wherein the main frame and the closure are or may be substantially as previously described. The main frame is shown at 62 and the closure frame is shown at 64. In lieu of the plate 22 a similar but smaller plate 66 is provided. Horizontally movable in at least one guide 70 on the front of the plate 66 is a bar 72. The left portion of the bar 72 extends through an aperture 35 in a small plate 73 on the closure frame 64, the said plate serving as a supplemental guide. The bar 72 normally projects through an aperture in a small plate 74 on the main frame 62. The said bar 72 constitutes means carried by the closure and relatively movable into and out of engagement with the main frame for retaining the closure in closed position or for releasing it.

Carried by the bar 72 at the front thereof is a handle 76 adapted for relatively moving the said bar into and out of engagement with the main frame. A similar handle 78 is carried by the bar 72 at the rear thereof, this last said handle projecting through a horizontal slot 79 in the plate 66. The handle 78 is also adapted for relatively moving the said bar into and out of engagement with the main frame.

Carried by the bar 72 and movable with it is a member 80 corresponding in function with the member 50. The member 80 is adjacent the plate 66 and at the front thereof. The member 80 and the plate 66 are provided respectively with slots 82 and 84 which are similar to the slots 52 and 54 and which are in register with each other when the retaining means or bar 72 is in its frame engaging position as shown. The plate 66 is provided with an opening 86 similar to the opening 56 and immediately below the slots 82 and 84, the said opening 86 being of such size as to be adapted to receive a padlock body such as 58. The shackle 60 of the padlock extends through the slots 82 and 84 and serves to prevent relative movement of the member 80, thus serving to prevent relative movement of the retaining means or bar 72 out of its main frame engaging position.

The padlock as shown in Figs. 6 and 7 functions exactly as previously described and repetition of the description is unnecessary.

The invention claimed is:

1. In a device of the class described, the combination of a frame adapted to be mounted at a window or the like, a closure having opposite sides and hinged to the frame so as to be movable to and from a closed position which closure is constructed to prevent manual access therethrough from either side to the other, means car-

ried by the closure and relatively movable into and out of engagement with the frame for retaining the closure in closed position or for releasing it, two manually operable handles carried by the closure and respectively located at the said opposite sides thereof both of which handles are connected with the retaining means for moving the latter into and out of retaining engagement with the frame upon movement of either handle, one of the said handles being located at and accessible at one side of the closure and the other of the said handles being located at and accessible at the other side of the closure, and a lock normally serving to lock the retaining means in retaining engagement with the frame which lock has a single operating means that is accessible at each side of the closure for effecting manual unlocking so as to release the retaining means for movement by either handle out of its said retaining engagement.

2. In a device of the class described, the combination of a frame adapted to be mounted at a window or the like, a closure having opposite sides and hinged to the frame so as to be movable to and from a closed position which closure is constructed to prevent manual access therethrough from either side to the other, means carried by the closure and relatively movable into and out of engagement with the frame for retaining the closure in closed position or for releasing it, two manually operable handles carried by the closure and respectively located at the said opposite sides thereof both of which handles are connected with the retaining means for moving the latter into and out of retaining engagement with the frame upon movement of either handle, one of the said handles being located at and accessible at one side of the closure and the other of the said handles being located at and accessible at the other side of the closure, and a lock normally connected with one handle and normally serving to lock the last said handle and thereby lock the retaining means in retaining engagement with the frame which lock has a single operating means that is accessible at each side of the closure for effecting manual unlocking so as to release the last said handle and thus release the retaining means for movement by either handle out of its said retaining engagement.

3. In a device of the class described, the combination of a frame adapted to be mounted at a window or the like, a closure having opposite sides and hinged to the frame so as to be movable to and from a closed position which closure is constructed to prevent manual access therethrough from either side to the other, means carried by the closure and relatively movable into and out of engagement with the frame for retaining the closure in closed position and for releasing it, two manually operable handles carried by the closure and respectively located at the said opposite sides thereof both of which handles are connected with the retaining means for moving the latter out of retaining engagement with the frame upon movement of either handle, one of said handles being located at and accessible at one side of the closure and the other of said handles being located at and accessible at the other side of the closure, a movable member on the closure at said one side thereof and connected to said one handle and movable in parallelism with said one side of the closure, and a lock normally connected with said movable member and normally serving to lock said movable member and said one handle and thereby lock the retaining means in retaining engagement with the frame which lock has a single operating means that is accessible at each side of the closure for effecting manual unlocking so as to release the said movable member and thus release said one handle and the retaining means for movement of the retaining means from retaining engagement with the frame.

4. In a device of the class described, the combination of a frame adapted to be mounted at a window or the like, a closure having opposite sides and hinged to the frame so as to be movable to and from a closed position

which closure has a small opening therein but is nevertheless constructed to prevent manual access through the closure from one side to the other, means carried by the closure and relatively movable into and out of engagement with the frame for retaining the closure in closed position or for releasing it, two manually operable handles carried by the closure and respectively located at the said opposite sides thereof both of which handles are connected with the retaining means for moving the latter into and out of retaining engagement with the frame upon movement of either handle, one of the said handles being located at and accessible at one side of the closure and the other of said handles being located at and accessible at the other side of the closure, a movable member on the closure at one side thereof and connected for relative movement in unison with the retaining means which member is adjacent the said closure opening and is movable in parallelism with the last said closure side, and a manually operable padlock normally engaging the said member to lock it against relative movement and to thereby lock the retaining means in retaining engagement with the frame, the said padlock being in the said closure opening and being thereby accessible at each side of the closure for manual unlocking so as to release the said member and to thereby release the retaining means for movement by either handle out of its said retaining engagement.

5. In a device of the class described, the combination of a frame adapted to be mounted at a window or the like, a closure having opposite sides and hinged to the frame so as to be movable to and from a closed position which closure has a small padlock receiving opening therein and also has an aperture therein adjacent the said opening, the said closure notwithstanding the said opening and aperture being constructed to prevent manual access through the closure from either side thereof to the other, means carried by the closure and relatively movable into and out of a frame engaging position for retaining the closure in closed position or for releasing it, two manually operable handles carried by the closure and respectively located at the said opposite sides thereof both of which handles are connected with the retaining means for moving the latter into and out of retaining engagement with the frame upon movement of either handle, one of the said handles being located at and accessible at one side of the closure and the other of the said handles being located at and accessible at the other side of the closure, and a movable member on the closure at one side thereof and connected for relative movement in unison with the retaining means which member is adjacent the said closure opening and is movable in parallelism with the last said closure side, the said member having an aperture therein positioned to register with the said aperture in the closure when the member is in the position corresponding to the frame engaging position of the retaining means, the said apertures in the closure and in the movable member when in register being adapted for receiving the shackle of a padlock which has its body in the said closure opening and which is accessible at each side of the closure for unlocking.

6. A device as set forth in claim 5, wherein the apertures in the closure and in the movable member are slots substantially perpendicular to the adjacent edge of the closure opening and having lengths greater than the major transverse dimension of the padlock shackle.

7. In a device of the class described, the combination of a frame adapted to be mounted at a window or the like, a closure having opposite sides and hinged to the frame so as to be movable to and from a closed position which closure is constructed to prevent manual access therethrough from either side to the other, means carried by the closure and relatively movable into and out of a frame engaging position for retaining the closure in closed position or for releasing it, a manually operable pivoted handle carried by the closure at one side thereof and connected with the retaining means for moving the

latter into and out of retaining engagement with the frame, a second manually operable pivoted handle carried by the closure at the opposite side thereof and at a different level, a link connecting the two handles for enabling the second handle to move the retaining means into and out of retaining engagement with the frame, and a lock normally serving to lock the retaining means in retaining engagement with the frame which lock has a single operating means that is accessible at each side of the closure for effecting manual unlocking so as to release the retaining means for movement by either handle out of its said retaining engagement.

8. In a device of the class described, the combination of a frame adapted to be mounted at a window or the like, a closure having opposite sides and hinged to the frame so as to be movable to and from a closed position which closure is constructed to prevent manual access therethrough from either side to the other, means carried by the closure and relatively movable into and out of a frame engaging position for retaining the closure in closed position or for releasing it, a manually operable pivoted handle carried by the closure at one side thereof and connected with the retaining means for moving the latter into and out of retaining engagement with the frame, a second manually operable pivoted handle carried by the closure at the opposite side thereof and at a different level, a link connecting the two handles for enabling the second handle to move the retaining means into and out of retaining engagement with the frame, and a lock normally connected with one handle and normally serving to lock the last said handle and thereby lock the retaining means in retaining engagement with the frame which lock has a single operating means that is accessible at each side of the closure for effecting manual unlocking so as to release the last said handle and thus release the retaining means for movement by either handle out of its said retaining engagement.

9. In a device of the class described, the combination of a frame adapted to be mounted at a window or the like, a closure having opposite sides and hinged to the frame so as to be movable to and from a closed position which closure has a small opening therein but is nevertheless constructed to prevent manual access through the closure from one side to the other, means carried by the closure and relatively movable into and out of a frame engaging position for retaining the closure in closed position or for releasing it, a manually operable pivoted handle carried by the closure at one side thereof and spaced substantially above the closure opening which handle is connected with the retaining means for moving the latter into and out of retaining engagement with the frame, a second manually operable pivoted handle carried by the closure at the opposite side thereof and at a lower level adjacent the said closure opening, a link connecting the two handles for enabling the second handle to move the retaining means into and out of retaining engagement with the frame, a member pivotally movable in unison with the second handle, and a manually operable padlock normally engaging the said member to lock it against pivotal movement and to thereby lock the retaining means in retaining engagement with the frame, the said padlock being in the said closure opening and being thereby accessible at each side of the closure for manual unlocking so as to release the said member and to thereby release the retaining means for movement by either handle out of its said retaining engagement.

10. In a device of the class described, the combination of a frame adapted to be mounted at a window or the like, a closure having opposite sides and hinged to the frame so as to be movable to and from a closed position which closure has a small padlock receiving opening therein

and also has an aperture therein adjacent the said opening, the said closure notwithstanding the said opening and aperture being constructed to prevent manual access through the closure from either side thereof to the other, 5 means carried by the closure and relatively movable into and out of a frame engaging position for retaining the closure in closed position or for releasing it, a manually operable pivoted handle carried by the closure at one side thereof and spaced substantially above the closure opening which handle is connected with the retaining means for moving the latter into and out of retaining engagement with the frame, a second manually operable pivoted handle carried by the closure at the opposite side thereof and at a lower level adjacent the said closure opening, a 15 link connecting the two handles for enabling the second handle to move the retaining means into and out of retaining engagement with the frame, and a movable member on the closure connected with the second handle for movement therewith which said member has an aperture 20 therein positioned to register with the said aperture in the closure when the member is in the position corresponding to the frame engaging position of the retaining means, the said apertures in the closure and in the movable member when in register being adapted for receiving the shackle 25 of a padlock having its body in the said closure opening and accessible at each side of the closure for unlocking.

11. In a device of the class described, the combination of a main frame adapted to be mounted at a window or the like, a closure comprising a second frame hinged at one edge thereof to the main frame and movable to and from a closed position and also comprising a metal plate secured to the second frame at the edge thereof opposite the hinged edge and further comprising a wire mesh connected with the second frame and with the said plate and 30 serving in cooperation with the plate to cover the area within the second frame, the said plate having an opening in its lower portion of such size as to be adapted to receive the body of a padlock and also having an aperture therein adjacent the said opening, means carried by the closure and relatively movable into and out of a frame engaging 35 position for retaining the closure in closed position or for releasing it, a manually operable pivoted handle carried by the said plate at one side thereof and near the top which handle is connected with the retaining means for 40 moving the latter into and out of retaining engagement with the frame, a second manually operable pivoted handle carried by the said plate at the opposite side thereof and adjacent the said plate opening, a link connecting the two handles for enabling the second handle to move the 45 retaining means into and out of retaining engagement with the frame, and a movable member on the closure connected with the second handle for movement therewith which said member has an aperture therein positioned to 50 register with the said aperture in the plate when the member is in the position corresponding to the frame engaging position of the retaining means, the said apertures in the plate and in the movable member when in register being adapted for receiving the shackle of a padlock having its body in the said plate opening and accessible at each side 55 of the closure for unlocking.
